UNITED STATES PATENT OFFICE

EUGENE C. HEALY, OF MELROSE, AND NICHOLAS D. WHALEN, OF ATTLEBORO,
MASSACHUSETTS

CURTAIN PULL

Application filed May 6, 1931. Serial No. 535,326.

Our invention relates to pulls for curtains or shades for use in buildings, automobiles or elsewhere.

An essential object of our invention is to prevent the excessive swaying, folding, entangling, or other distortion of the curtain pull, particularly when located in a vehicle, or when subjected to strong currents of air.

Another object is to provide a facile and effective means for assembling the parts.

A further object is to attain these ends in a slightly, strong, and inexpensive structure.

To the above ends essentially our invention consists in such parts and in such combinations of parts as fall within the scope of the appended claims.

In the accompanying drawings which form a part of this specification,

Figure 1 is a front elevation of a curtain pull embodying our invention,

Figure 2, a fragmentary side elevation of the same,

Figure 3, a fragmentary section of the same taken on line 3—3 of Figure 1,

Figure 4, a perspective view of the attaching or clip portion and of the ring engaged thereby,

Figure 5, a perspective view of the split ring, and

Figure 6, a plan view of the thimble.

Like reference characters indicate like parts throughout the views.

In the form thereof herein illustrated our curtain pull is composed of a knob or hand hold 10 comprising a body 11 and a truncated conical vertical centering projection 12. The body is composed of a wooden core 15 having an outline corresponding with that of the knob, provided with a concave cavity 18 in its lower portion and a central vertical passage 19 from the cavity through the core. The exterior of the core has an external covering or sheath 21 formed by the coils 22 of a textile cord fixed to the surface of the core by glue or the like.

Seated in the cavity is a button 23 provided with a central hole 24 and having a convex top to fit the concavity. Interposed between the button and core is a thread loop

25 upon which is looped the depending threads 26 constituting a fringe 27.

The strands 29 of an upwardly directed loop 30 pass through the core passage 19 and snugly through the button hole 24 and have their lower ends depending below the button and embraced adjacent their ends by a split clamping ring 32 of pliable metal.

A metallic tapering thimble 34 rests upon the knob body 11 adjacent the centering projection 12 and extending above the latter. The upper end of the thimble is provided with a central circular opening 39 through which loosely passes the upper extremity of the loop 30. Communicating with the opening at diametrically opposite sides thereof are rectangular recesses 41.

The loop 30 passes through a flat suspension ring 42 which is slidably seated in the thimble in the recesses 41 where it is maintained by the loop against escape therefrom.

The suspension ring is supported by an attaching member represented in a general way by 44 comprising opposed plates 45 connected at their lower ends by a depending integral flat or transversely rectangular loop 46 adapted to embrace the ring 42 which passes therethrough. Upon the upper ends of the plates 45 are inwardly directed, and preferably downwardly inclined prongs 48. The material of the member 44 is pliable.

In order to apply the latter to the stick 50 of a shade 51 it is first distended into some such position as shown in broken lines in Figure 3, and then, manually or by pliers, compressed to force the prongs 48 into the stick 50, and bind the loop 46 into rigid engagement with the ring 42.

Any desired limited degree of sway permitted the knob is determined by the degree of tension of the loop 30 upon the suspension ring 42, which tension is effected by the height of the clamping ring 32 upon the loop strands 29. To apply the clamping ring in assembling it is manually slipped up over the depending ends of the strands against the bottom of the button 23 with the desired degree of pressure while the ends are being held under tension, and while so positioned the clamping ring, in the open position

shown in Figure 5, is tightly clamped together and immovably secured upon the strands.

While we have described specific constructional features, it is obvious that desired changes in the proportion and the arrangement of the parts may be made, without departing from the spirit and the scope of the invention as defined in the appended claims.

10 We claim:—

1. In a curtain pull, a knob, a thimble upon the knob provided in its top with an opening and with recesses communicating with the opening, a loop in the opening carried by the knob, a suspension ring through which the loop passes registering in the recesses, and an attaching member supporting the ring.

2. In a curtain pull, a knob provided with a cavity in its bottom and with a central vertical passage extending therefrom, a thimble resting upon the knob provided in its top with an opening and with oppositely disposed recesses communicating with the opening, a loop in the opening including strands extending through the passage, a button in the cavity engaging the strands, a suspension ring through which the loop passes registering in the recesses, and an attaching member supporting the ring.

3. In a curtain pull, a knob provided with a cavity in its lower portion and with a passage leading upwardly therefrom, a thimble upon the knob provided in its top with an opening and with recesses extending therefrom, a loop in the opening including strands depending through the thimble and passage, a button in the cavity provided with a hole through which the strands depend, a fringe supported by the button, a clamping member upon the strands abutting against the bottom of the buckle, a suspension ring through which the loop passes registering in the recesses, and an attaching member supporting the ring.

4. In a curtain pull, a knob comprising a body and a vertical centering projection, said body being provided with a cavity, and the body and the projection being provided with a passage extending from the cavity through the body and projection, a conical thimble resting upon the body concentric with the projection provided with an opening in its top and with recesses communicating with the openings, a ring in the recesses, a loop in the opening passing through the ring and including strands traversing the passage, a button in the cavity attached to the strands, and an attaching member supporting the ring.

5. In a curtain pull, a knob, a thimble upon the knob provided in its top with an opening, and with recesses extending from the opening, a loop in the opening engaging the knob, a ring provided with flat side portions

engaging the loop and extending into the recesses, and a pliable attaching member comprising opposed plates, a flat loop integral with the lower portions of the plates and embracing the flat side portions of the ring, and prongs upon the plates above the second loop.

6. In a curtain pull, a knob, a thimble upon the knob provided in its top with an opening, a loop in the opening carried by the knob, and a suspension ring through which the loop passes frictionally engaging the thimble.

7. In a curtain pull, a knob, a thimble upon the knob provided in its top with an opening, a loop engaged by the knob and extending into the opening, and a suspension ring tightly engaged by the loop.

8. In testimony whereof we have affixed our signatures.

EUGENE C. HEALY.
NICHOLAS D. WHALEN.
